UNITED STATES PATENT OFFICE.

BENJAMIN F. ELLIS AND GEORGE D. GREENE, OF LOS ANGELES, CALIFORNIA.

UNDERGROUND CESSPOOL.

1,150,510.

Specification of Letters Patent. Patented Aug. 17, 1915.

Application filed May 12, 1915. Serial No. 27,490.

To all whom it may concern:

Be it known that we, BENJAMIN F. ELLIS and GEORGE D. GREENE, citizens of the United States, residing at Los Angeles, in the county of Los Angeles and State of California, have invented new and useful Improvements in Underground Cesspools, of which the following is a specification.

Our invention relates to improvements in cess-pools in which a drain connection is provided for draining the water therefrom into a drain bore from which the water percolates into the ground.

A cess-pool as usually constructed consists of a cistern-like underground cavity built with wooden or brick walls, the latter being arched over at the top, which is usually provided with a man-hole, and a cover therefor. The latter is usually about two feet below the level of the ground and is covered with earth. The sewage and waste water flows into the cess-pool which acts as a septic tank, the operation of which is well understood, causing the solid matters to settle on the bottom forming a sediment while oil and grease will float on the top. It is frequently necessary to remove the water intermediate between the top layer of grease and the sediment at the bottom, which is done by uncovering the man-hole and inserting suction hose attached to a pump into the cess-pool, said pump taking out the liquid contents of the cess-pool positioned between the layer of grease and the sediment. At greater intervals of time it is necessary to remove the sediment and the grease from the cess-pool.

It is an object of our invention to avoid the necessity of pumping out and hauling off the liquid contents as described by drilling or boring a hole leading to approximately the middle of the cess-pool, said bore extending from the cess-pool at an acute angle upwardly and communicating with a vertical drain bore. The drain bores are drilled or dug adjacent to the cess-pool and are made of a depth sufficient to reach a bed of sand or gravel, which acts as a filter retaining all matter which might prove injurious to health if allowed to percolate and reach a source of water supply. When a layer of sand or gravel is not available it is necessary to construct the drain bore of a greater depth and provide a great number of drainage fissures at the bottom thereof by the explosion of a small charge of dy-

namite. This construction provides means for draining off the clear water automatically without allowing any sediment to pass through and, at the same time, retaining the grease from passing into said drain bore, thus preventing the clogging up the sand filter or drainage fissures above referred to.

The provision of a bore leading obliquely from substantially the middle of the cess-pool to the drain bore is objectionable in this respect: The water flowing down one side of the drain bore gradually erodes the wall, causing the clay and other heavy earths to be washed down into the bottom of said bore and clogging the drainage through the sand, gravel and other lighter soils, thereby necessitating the frequent cleaning out of the drain bore.

It is another object of our invention to provide novel and improved means to overcome this difficulty and to prevent the erosion of the drain bore caused by the water flowing down the walls thereof. This we accomplish by means of a drain connection pipe provided with a goose neck downwardly extending into the drain bore, whereby the water drained from the cess-pool will fall straight down, having no contact with the walls of the drain bore before it strikes the bottom.

The accompanying drawing forming a part of this specification shows a vertical cross section of a cess-pool provided with our improved goose neck drain connection.

10 represents the cess-pool constructed with brick walls 12, the latter forming an arch at the top provided with a man-hole 13 having a cover 14.

We have shown two drain bores 16 located at opposite sides of the cess-pool though any number of drain bores may be provided as desired. These drain bores are constructed deep enough until they strike a layer of sand and gravel. If this is not possible because of the absence of sand and gravel layers in the locality where the cess-pool is located, a small charge of dynamite is exploded at the bottom of these drain bores in order to produce the necessary drainage fissures. Both the layer of sand and gravel and the drainage fissures act as filters for the water drained from the cess-pool. A drainage connection pipe 17 provided with a goose neck 18 at its outer end, preferably contracted toward the mouth, extends down-

wardly into the drain bore. An inlet opening 19 located near the top of the cess-pool admits the sewage and waste water thereto.

From the foregoing description the operation of our improved cess-pool will be easily understood. The cess-pool is gradually filled with sewage and waste water through inlet 19. The bacteria which are present will cause said cess-pool to function as a septic tank causing the separation of the matter carried in suspension by the liquid in the cess-pool. Such septic action will separate the liquid into three distinct layers, the lowest a sediment of the more solid particles and a top layer of comparatively slight thickness of grease and oil, and an intermediate layer of comparatively clear water. The water constitutes by far the greater portion of the contents of the cess-pool. The inclined drain connection pipe 17 will drain this water into the drain bore whence it will percolate through the soil and sand. The contracted goose neck connection at the outer end of the drain connection pipe extending downwardly into the drain bore will cause the water to flow straight down without coming into contact with the walls of the drain bore, thereby effectively preventing the erosion thereof and a consequent filling up of the lower part of the drain bores. By providing an inclined drain connection pipe the water only will be drained off but the layer of grease will be retained in the cess-pool because of said inclination of the drain connection pipe, as will be understood, no grease being able to enter said drain connection pipe nor flow over into the drain bores and cause clogging and stoppage of the natural drainage through the lighter earths and soils.

It is therefore seen that we have provided a simple and efficient means for automatically draining the water from a cess-pool yet retaining, on the one hand, the sediment and, on the other, the grease contained therein, and at the same time preventing the erosion of the walls of the drain bores, thereby maintaining the functioning of the cess-pool until such time when the layer of sediment and layer of grease make their removal from the cess-pool necessary.

We claim:

1. A cess-pool provided with a man-hole, an inlet to said cess-pool located near the top thereof, a vertical drain bore adjacent to said cess-pool, and a drain connection pipe establishing communication between said cess-pool and said drain bore, said drain connection pipe leading from substantially the middle of the cess-pool at an acute angle upwardly into said drain bore and being provided at its upper end with a contracted goose neck extending downwardly into the drain bore and out of contact of the walls of said drain bore, whereby the water from the cess-pool is drained into said drain bore yet the erosion of the walls of said drain bore is prevented, substantially as described. 55 60 65

2. A cess-pool provided with a man-hole, an inlet to said cess-pool located near the top thereof, a vertical drain bore adjacent to said cess-pool, and a drain connection pipe establishing communication between said cess-pool and said drain bore, said drain connection pipe leading from substantially the middle of the cess-pool at an acute angle upwardly into said drain bore and being provided at its upper end with a contracted goose neck extending downwardly into the drain bore and out of contact of the walls of said drain bore, whereby the water from the cess-pool is drained into said drain bore yet the erosion of the walls of said drain bore is prevented, substantially as described. 70 75 80 85

3. A cess-pool provided with a man-hole, an inlet to said cess-pool located near the top thereof, a vertical drain bore adjacent to said cess-pool, and a drain connection pipe establishing communication between said cess-pool and said drain bore, said drain connection pipe leading from substantially the middle of the cess-pool at an acute angle upwardly into said drain bore, whereby the water from the cess-pool is drained into said drain bore, substantially as described. 90 95

In witness that we claim the foregoing we have hereunto subscribed our names this 5th day of May, 1915.

BENJAMIN F. ELLIS.
GEO. D. GREENE.
